UNITED STATES PATENT OFFICE.

LAFE OREN ROBERTS, OF PORTLAND, OREGON.

SHUTTLE-CLAMP.

1,360,582.

Specification of Letters Patent. Patented Nov. 30, 1920.

Application filed February 28, 1920. Serial No. 362,145.

To all whom it may concern:

Be it known that I, LAFE O. ROBERTS, a citizen of the United States, and a resident of Portland, in the county of Multnomah and State of Oregon, have invented certain new and useful Improvements in Shuttle-Clamps, of which the following is a specification.

My invention is an improvement in shuttle clamps, and has for its object to provide mechanism of the character specified by means of which a shuttle may be firmly gripped and held during winding of the thread.

15 In the drawings:

Figure 1 is a perspective view showing the device in use;

Fig. 2 is a side view;

Fig. 3 is a view at right angles to Fig. 2;

20 Fig. 4 is a plan view of the clamp.

The present embodiment of the invention is shown in connection with a shuttle 1, and the improvement comprises a clamp formed from a strip of sheet metal of suitable weight and resiliency. This strip is bent into U-shape, to form a body 2 and arms 3 extending approximately parallel, and each of these arms is provided at its free end with a transversely extending groove formed on 25 its inner face, that portion of the arm beyond the groove being bent angularly inward, as shown at 5, at approximately a right angle to the body of the arm.

Thus the device as a whole is U-shaped, consisting of a body and arms, each arm 35 having a transverse groove on its inner face at its free end for engaging the edge of the side of the shuttle.

By grasping the side of the shuttle, as shown in Figs. 1 and 2, the shuttle may be 40 firmly held during the winding of the thread. The shuttle will be held in the left hand while the thread will be wound with the right. Referring to Fig. 4, it will be seen that each of the arms 4 is curved 45 slightly inward intermediate its ends, to fit the fingers and thumb when grasping the same.

I claim:

1. A device of the character specified comprising a clamp of substantially U-shape, 50 consisting of a body and arms extending approximately parallel, each arm having at its free end and on its inner face a transversely extending groove for engagement by the 55 edge of a shuttle face, the extremity of the arm being bent laterally inward beyond the groove.

2. A device of the character specified comprising a clamp of substantially U-shape, 60 consisting of a body and arms extending approximately parallel, each arm having at its free end and on its inner face a transversely extending groove for engagement by the edge of a shuttle face.

LAFE OREN ROBERTS.
